COMBINED CAN SEALING PLUG AND RETAINER RING THEREFOR

Richard L. Gedell, 7960 Jackson St. NE,
Spring Lake Park, Minn. 55432

Filed Aug. 18, 1972, Ser. No. 281,793

Term of patent 14 years

Int. Cl. D9—07

U.S. Cl. D9—255

FIG. 1

FIG. 2

FIG. 3

FIG. 4

FIG. 5

FIG. 1 is a top plan view of the combined can sealing plug and retainer ring therefor showing my new design;

FIG. 2 is a front edge view;

FIG. 3 is a bottom plan view of FIG. 1;

FIG. 4 is a right end view of FIG. 1;

FIG. 5 is a left end view of FIG. 1; and

FIG. 6 is an enlarged scale cross-sectional view taken along line 6—6 of FIG. 1.

I claim:

The ornamental design for a combined can sealing plug and retainer ring therefor, as shown and described.
